US00D753159S

(12) **United States Design Patent**
Hiramatsu et al.

(10) **Patent No.:** **US D753,159 S**
(45) **Date of Patent:** **** Apr. 5, 2016**

(54) **DISPLAY PANEL OR SCREEN WITH
GRAPHICAL USER INTERFACE**

(71) Applicant: **Sony Computer Entertainment Inc.**,
Tokyo (JP)

(72) Inventors: **Shuji Hiramatsu**, Tokyo (JP); **Taku Sugawara**, Tokyo (JP); **Shinji Kimura**, Los Angeles, CA (US)

(73) Assignee: **Sony Computer Entertainment Inc.**,
Tokyo (JP)

(**) Term: **14 Years**

(21) Appl. No.: **29/464,841**

(22) Filed: **Aug. 21, 2013**

(30) **Foreign Application Priority Data**

Aug. 14, 2013 (JP) D2013-018706

(51) **LOC (10) Cl.** **14-04**

(52) **U.S. Cl.**

USPC **D14/486**

(57) **CLAIM**

The ornamental design for a display panel or screen with graphical user interface, as shown and described.

DESCRIPTION

The FIGURE is a front elevational view of a display panel or screen with graphical user interface showing our new design. The broken lines in the FIGURE represents portions of the display panel or screen with graphical user interface that form no part of the claimed design.
